GASEOUS ELECTRIC DISCHARGE DEVICE

Eduard G. Dorgelo, Eindhoven, Netherlands, assignor to General Electric Company, a corporation of New York

Application April 16, 1935, Serial No. 16,637
In the Netherlands April 19, 1934

2 Claims. (Cl. 176—124)

The present invention relates to gaseous electric discharge devices generally and more particularly the invention relates to starting and operating circuits for such devices.

I have observed that in illuminating systems comprising a plurality of transformers having the primaries thereof connected in series across the terminals of an alternating current source and the secondaries thereof connected to a gaseous electric discharge lamp device of the type having thermionic electrodes and operating with an elevated container temperature, such as sodium vapor lamps, the number of lamps which can be successfully started and operated on the voltage of the current source is limited. When the number of lamps is too large the thermionic electrodes thereof are not heated at all or are heated very slowly to the temperature most favorable for the efficient operation of the lamp. The lamps thus require an appreciable time to attain the temperature at which they operate at maximum efficiency and perhaps do not reach such temperature at all.

The object of the present invention is to increase the number of gaseous electric discharge vapor lamps which can be successfully started and operated in circuits of the above type. A further object of the invention is to shorten the starting period of such lamps in such circuits. Still further objects and advantages attaching to the device and to its use and operation will be apparent to those skilled in the art from the following particular description.

The invention attains its objects by connecting a choke coil in parallel with a number of transformer primaries and in series with the other transformer primaries in the circuit. When potential is applied to the above described circuit a higher current flows through the transformer primaries connected in series with the choke coil than would flow therethrough in the absence of said choke coil. When the electrodes are of the type having a heater for the electron emitting material, which heater is connected across a few turns of the transformer secondary, the higher transformer current rapidly heats the electrodes to the electron emitting, discharge supporting temperature thereof and the lamp container is rapidly raised to the elevated temperature at which the lamp operates efficiently. When the electrodes are of the type wherein the electron emitting material is heated directly by the discharge incident thereto and the discharge current flow therethrough the higher transformer current causes a higher discharge current between

the electrodes, which are cold when the circuit is closed, and the electrodes are rapidly heated to the electron emitting, discharge supporting temperature thereof and the lamp container is rapidly raised to the elevated temperatures at which the lamp operates efficiently. When the operating current is flowing through these lamps the potential difference between the ends of the choke-coil is such that current flow through the primaries of the transformers connected in parallel with said choke-coil is sufficient to rapidly heat the thermionic electrodes of the lamps connected to the secondaries of said transformers and the containers of the lamps to the temperature at which said lamps operate efficiently.

In the drawing accompanying and forming part of this specification an embodiment of the invention is shown schematically.

Referring to the drawing the new and novel illuminating system comprises a plurality of gaseous electric discharge lamp devices 1 and 2 each of which comprises an elongated container having a pair of electrodes 3 sealed therein and mounted at opposite ends thereof and a gaseous atmosphere therein, such as neon and sodium vapor. A quantity of sodium is introduced into the container of the lamp during the manufacture thereof and is the source of the sodium vapor. Said electrodes 3 are electron emitting when heated and each of said electrodes 3 comprises a heater filament, such as a tungsten or a nickel filament, coated or impregnated with an electron emitting material, such as barium and barium oxide. When desired the heater filament is wrapped around a bar or rod of electron emitting material. For purposes of simplicity of illustration the lamps 1 and 2 are shown schematically in the drawing. Since the structure of this type of lamp is now well known further description and illustration thereof has been omitted.

Each of the discharge lamps 1 connected to the secondary 4 of a transformer 4, 6 and each of the lamps 2 is connected to the secondary 5 of a transformer 5, 7. The primaries 6 and 7 of said transformers 4, 6 and 5, 7 are connected in series across the terminals 8 of an alternating current source. The heating current for each of said electrodes 3 is supplied by a few turns at the end of the secondary 4 or 5 of said transformers 4, 6 or 5, 7, respectively. The alternating current source for the above described circuit is, preferably, a constant current transformer. A choke coil 9 is connected in parallel to the primaries 7 and in series with the primaries 6 with respect to the current source 8.

When potential is applied to the above described circuit a higher current flows through the primaries 6 than would flow therethrough if said choke coil 9 were omitted. The higher current flow in the primaries 6 induces a correspondingly higher current in the secondaries 4 which rapidly heats the electrodes 3 to their electron emitting, discharge supporting temperature and the discharge in the gas between the electrodes 3 in each of said lamps 1 starts shortly after potential is applied to the circuit. The lamp container is rapidly heated by said gas discharge to the vaporization temperature of the sodium and the lamp is an efficient source of sodium vapor light.

When the operating discharge current is flowing in the lamps 1 the potential difference between the ends of the choke coil 9 is considerably greater than during the starting period of said lamps 1. The size of the choke coil 9 with relation to the number of lamps 2 is such that the potential difference between the ends of the choke coil 8 after the lamps 1 have started is sufficient to start the lamps 2 into operation.

When all the lamps 1 and 2 have been started into operation the current flow through the tubes 2 is slightly lower than the current flow through the lamps 1, due to the choke coil 9. However, since the current through said choke-coil 9 lags about 90° with respect to the current flow through the lamps 2, the difference between the lamp 2 current and the lamp 1 current is so small as to be insignificant and it is not necessary to disconnect the choke-coil 8 after the lamps have been started into operation.

When desired, the electrodes 3 are of the type which are heated to and maintained at an electron emitting, discharge supporting temperature by the discharge current. In this case the high current flowing through the secondaries 5 causes a more intense glow-discharge current between the electrodes 3 which rapidly brings the lamps 2 to their elevated operating temperature.

While I have shown and described and have

pointed out in the annexed claims certain novel features of the invention, it will be understood that various omissions, substitutions and changes in the forms and details of the device illustrated and in its use and operation may be made by those skilled in the art without departing from the broad spirit and scope of the invention, for example, the transformers 4, 6 and 5, 7 are auto-transformers, when desired, and the gaseous atmosphere of the lamps consists of or comprises other metal vapors, such as mercury vapor, cadmium vapor, magnesium vapor, or thallium vapor.

What I claim as new and desire to secure by Letters Patent of the United States, is:—

1. An illuminating system comprising in combination a current source, a plurality of gaseous electric discharge lamps, a plurality of transformers therefor, the primaries of said transformers being connected in series across the terminals of said current source and a choke coil connected in series with some of said transformer primaries and in parallel with the others of said transformer primaries with respect to said current source, said choke-coil starting said lamps connected to the transformers connected in parallel thereto after said lamps connected to said transformers connected in series therewith have started.

2. An illuminating system comprising in combination a constant current source, a plurality of gaseous electric discharge lamps, a plurality of transformers therefor, the primaries of said transformers being connected in series across the terminals of said current source and a choke coil connected in series with some of said transformer primaries and in parallel with the others of said transformer primaries with respect to said current source, said choke-coil starting said lamps connected to the transformers connected in parallel thereto after said lamps connected to said transformers connected in series therewith have started.

EDUARD G. DORGELO.
